GUN AND GUN CARRIAGE

Charles Dennistoun Burney, Baynards Park,
near Cranleigh, EnglandApplication September 6, 1945, Serial No. 614,715
In Great Britain January 1, 1943Section 1, Public Law 690, August 8, 1946
Patent expires January 1, 1963

1 Claim. (Cl. 89—40)

1

The present invention relates to recoilless guns of the kind in which the gun barrel does not require any mechanism for absorbing the recoil shock on firing and does not transfer any substantial recoil shock to the gun mounting or carriage. The term "recoilless" is used herein to denote a gun in which the whole or substantially the whole of the barrel recoil is eliminated and no shock or substantially no shock is transferred to the mounting. In some instances, however, a small recoil shock may be transferred to the mounting and in some cases a degree of barrel recoil may be allowed for the purpose of operating automatic loading mechanism.

The invention has for its main object to provide an improved construction of mobile recoilless gun adapted for dropping from aircraft. The invention is primarily devised for application to recoilless guns as described in the specification of my prior concurrent patent application, Serial No. 552,347, filed September 1, 1944, for improvements in or related to ordnance and small arms, although it is also applicable to other recoilless guns.

A further important object is to enable guns of the kind set forth to be carried by and dropped from aircraft as normally built and adapted for carrying and dropping torpedoes, so that it is unnecessary to build new aircraft or make substantial alterations to existing aircraft for carrying and dropping guns.

According to the main feature of the invention, I provide a mobile recoilless gun in which the barrel is supported on horizontal trunnions by a bracket which is rotatable on an underframe, wheeled at or near one end, about a vertical pivot disposed between the wheels at one end of the underframe and the other end of the underframe, but nearer to the wheeled end of the underframe than the other, and wherein the centre of gravity of the gun proper lies between the muzzle and the vertical pivot, so that with the major portion of the underframe constituting a false trail extending forwardly beneath the gun barrel, unobstructed access is obtained to the breech end of the gun overhanging the wheels, and the gun barrel and mounting as a whole forms a stable structure, both for firing and transport. Thus in its firing position, as well as during transport, the gun barrel extends over the major portion of the underframe, in which respect the gun differs from normal guns, in the case of which in the firing position the major portion of the underframe usually forms a trail extending rearwardly i. e. oppositely to the gun

2

barrel. For this reason the major and forwardly extending part of the underframe is herein referred to as a "false trail."

An important advantage of locating the vertical pivot nearer to the wheeled end of the underframe than the other, which arises in the case of guns according to the present invention, in which the barrel in its normal firing position extends over the major portion of the underframe, with its breech end extending beyond the wheeled end of the underframe, is that there is no trail to obstruct access to the breech end of the gun for the purposes of loading and laying.

15 The gun is ready for loading on an aircraft with its barrel extending in its normal firing position, longitudinally over the major portion or false trail of the underframe, in which position the overall length of the gun and carriage as a whole is a minimum, and the gun and carriage form a compact structure which will occupy a minimum of space on or in an aircraft.

In consequence of the weight distribution of the gun in relation to the wheels and the underframe, with the barrel in its firing position overlying the false trail or major portion of the underframe, if the gun on its mounting is loaded in an aircraft with its barrel directed towards the tail of the aircraft, when it is dropped from the aircraft, say from a height of three or four feet, the gun as a whole will make a stable three point landing on its two wheels and the end of the false trail, and will travel forward on its wheels without overturning. Preferably, the false trail itself, which may be either of single or split type, carries at its rear end a shoe, or lever member, which is rotatable about an axis at right angles to the trail, in combination with a brake mechanism acting on the wheels of the gun carriage, which is operated by rotation of the shoe or lever caused by its engagement with the ground. By this means the gun carriage may be rapidly brought to rest after being dropped from an aircraft.

45 The gun with the barrel overlying the false trail or major portion of the underframe may be slung beneath the body of an aircraft, in a manner similar to a torpedo, by means of two arms which encircle the barrel of the gun, which arms are 50 simultaneously opened to release the gun when it is to be dropped. This mechanism may be similar to the torpedo mounting and dropping gear employed on torpedo carrying aircraft, the gun barrel taking the place of the torpedo, and it is contemplated that such aircraft could be used

for carrying and dropping guns according to this invention without material alteration.

To protect the gun carriage from injury when dropped and when being towed along the ground, suitable springs may be fitted between the wheels and the carriage of the gun. Although any suitable spring mechanism may be provided it is preferred to make use of a transverse spring spanning the axle, in a manner similar to that commonly employed in connection with motor cars. Provision may be made for locking the springs between the wheels and the gun, when the gun is swung into firing position, so as to prevent the possibility of movement on firing.

Means may be provided for clamping the muzzle end of the gun to the false trail of the carriage, so that the gun can be towed by means of the false trail, with the gun barrel clamped in this position. If the gun is to be provided with a shield, in order to permit rotation of the gun through 180° or 360°, the gun shield may be attached to the gun itself, the lower part of the shield being hinged to enable it to clear the wheels when the gun is being rotated. The shield on the gun may operate in conjunction with a lower shield mounted on the wheeled underframe.

If desired the protection afforded by the shield may be increased by employing disc wheels of armour plate and so mounting them on their axle trees that they can be rotated into a plane at right angles to the axis of the gun, so as in effect to form extensions of the shield in the downward direction. Adjustable means would, of course, be provided for locking the wheels either in this position or in their normal running position, with their planes parallel to the axis of the gun.

An important advantage of the invention when the gun is of the recoilless type described in the above-mentioned application, Ser. No. 552,347, involving considerable extension of the gun in rear of the trunnion axis, is that it permits a higher angle of elevation, than would be possible with a normal rearwardly extending trail, since there is no obstruction to depression of the breech end of the gun.

In order that the invention may be clearly understood and readily carried into practice, the invention is illustrated, by way of example only, in the accompanying drawings, in which:

Figure 1 is a side elevation of a recoilless field gun mounted on a carriage in accordance with the invention,

Figure 2 is a plan view thereof with the shield removed,

Figure 3 is a view showing the gun mounted for transport by an aeroplane; and

Figure 4 is a front view illustrating a modification of the field gun mounting of Figures 1 and 2.

As shown in Figures 1 and 2 a recoilless field gun, for example, of 3.45" calibre, is mounted on a carriage with its barrel 1 extending in the same direction as the false trail 2 of the carriage. The gun is mounted on trunnions 3 pivotally carried by a bracket or mount 4 rotatable about a vertical axis 5 projecting upwardly from a platform 6, which, together with the false trail 2, constitutes the chassis or underframe of the gun carriage. As will be seen, the axis of the trunnions 3 lies vertically above and is intersected by the axis of the vertical pivot 5.

The center of gravity G of the barrel lies between its muzzle 1a and the axis of the trunnions 3.

The platform 6 and false trail 2 are mounted on the wheels 7 and the axle structure 7a through the intermediary of suitable leaf spring structures 8, and the barrel 1 is adapted to be elevated about the trunnions 3 by the elevating gear 9. The leaf spring structures 8 are parallel and spaced apart along the axle structure 7a; each spring structure has one end thereof secured to the axle structure 7a. The opposite end of each spring structure 8 is secured to the false trail 2 at 25, and the false trail is supported by the spring structures 8 at the point 26 intermediate the length of the spring structures. For traversing the gun the traversing gear 10 is operated to rotate the mount 4 on the platform 6. To permit an all round traverse of the gun the barrel 1 may carry a shield 11 having hinged flaps 12 along its lower edge, as shown in Figure 1.

When out of action the barrel 1 is depressed towards the false trail 2, as indicated by the dotted lines in Figure 1, and secured to the false trail by a clamping device generally indicated at 13. The end of the false trail 2 is provided with an eye 16 or other fitting to enable the gun to be towed when desired.

When in action the protection afforded by the shield 11 may be increased if the wheels 7 are so mounted on the ends of their axle tree, that they may be rotated rearwardly about vertical axes 30 into positions at right angles to their normal running positions, as illustrated by Figure 4.

The gun may be slung beneath an aeroplane as illustrated by Figure 3, the barrel being gripped by clamps or bands 18 similar to those employed on aircraft for the slinging of torpedoes, and similar means being provided for opening or releasing the clamps or bands 18 when it is desired to drop the gun from the aeroplane at a short distance above the ground.

As the gun will land from an aeroplane with considerable forward velocity, it is desirable to provide it with braking means. For this purpose the false trail 2 may be fitted with a ground spike 19 which on landing engages with the ground and operates suitable rod and lever mechanism 20 coupled to the wheel brakes 21, so that the brakes of the wheels 7 are applied as soon as the spike 19 engages the ground.

The same braking mechanism will serve to prevent accidental movement of the gun carriage from its arranged firing position, the brakes being applied by hand operated mechanism in the usual way, so that the spike 19 is projected from the false trail into a position in which it can be forced into the ground so as to form an anchor opposing any forward or rearward movement of the gun from its firing position, due to any partial forward or rearward recoil of the mounting on firing, although the gun is preferably of 100% non-recoil type.

I claim:

In a gun carriage, a pair of spaced wheels, an axle structure supported by said wheels, a pair of spaced parallel leaf spring structures extending substantially horizontally from one side of said axle structure, a false trail positioned on the same side of the axle structure as said springs, the ends of the springs distant from the axle structure being secured to said false trail and the false trail being supported by said spring structures intermediate the length of the latter, a bracket carried by said false trail above and outwardly from said axle structure, said bracket being rotatable with respect to said trail on a

vertical axis, a second bracket having gun trunnions and pivotally connected to said first bracket on a horizontal axis lying a substantial distance above said axle structure, a recoilless gun barrel carried in said trunnions with its muzzle directed away from the axle structure to fire in the direction of said false trail, the center of gravity of said barrel being disposed between the barrel muzzle and said horizontal axis upon which said trunnion is rotatable.

CHARLES DENNISTOUN BURNETT.
